UNITED STATES PATENT OFFICE

170,631

WEDDING ANNIVERSARY PIN

Oscar G. Feltner, Jr., Dallas, Tex.

Application April 24, 1952, Serial No. 19,456

Term of patent 14 years

(Cl. D29—2)

To all whom it may concern:

Be it known that I, Oscar G. Feltner, Jr., a citizen of the United States, residing at Dallas, Dallas County, Texas, has invented a new, original, and ornamental Design for a Wedding Anniversary Pin, of which the following is a specification, reference being had to the accompanying drawing, forming a part hereof.

The dominant features of my design reside in those portions shown in full lines.

I claim:

The ornamental design for a wedding anniversary pin, substantially as shown and described.

OSCAR G. FELTNER, JR.
